Inventor:
Benjamin Skidmore, Jr.

By: *John J. Gandy*

UNITED STATES PATENT OFFICE.

BENJAMIN SKIDMORE, JR., OF CHICAGO, ILLINOIS.

FLUID-DISPLACING APPARATUS.

1,390,390.

Specification of Letters Patent. Patented Sept. 13, 1921.

Application filed August 21, 1919. Serial No. 318,984.

To all whom it may concern:

Be it known that I, BENJAMIN SKIDMORE, Jr., a citizen of the United States, residing at Chicago, in the county of Cook and State of Illinois, have invented certain new and useful Improvements in Fluid-Displacing Apparatus, of which the following is a specification.

This invention relates to improvements in fluid displacing apparatus, particularly adapted, though not necessarily limited in its use for creating a suction or pressure, and one of the objects of the invention is to provide an improved apparatus of this character embodying a rotor operating to displace the liquid in such a manner that little centrifugal force or turbine action will be imparted to the liquid, causing the liquid to be delivered under pressure and with little circumferential velocity.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention and in which—

30 Figure 1 is a view partly in vertical section and partly in elevation as taken on line 1—1, Fig. 2, of an apparatus of this character constructed in accordance with the principles of this invention.

35 Fig. 2 is a vertical sectional view as taken on line 2—2, Fig. 1.

Fig. 3 is a vertical sectional view taken on line 3—3, Fig. 1.

Fig. 4 is a front elevation of Fig. 5.

40 Fig. 5 is a side elevation of Fig. 4.

Fig. 6 is a detail vertical sectional view of the rotor.

Referring more particularly to the drawings the numeral 10 designates a casing of any suitable configuration and is provided with a liquid inlet 11. Passing through the casing is a shaft 12 journaled in suitable bearings 13 provided with the usual stuffing boxes 14. The shaft 12 preferably extends 45 beyond the casing and is journaled in additional bearings 15, having connected with one end thereof a clutch element 16 by means of which the shaft may be coupled with any suitable source of power.

50 Arranged within the casing is a fixed element 17 comprising a body portion and

spaced laterally projecting extensions 18 so as to form an intermediate space 19 into which the liquid which enters the casing through the opening 11 will pass. This element 17 is held against rotation in any suitable manner and is hollow to provide passages 20 which communicate with an annular groove or channel 21 in the body of the member, and this groove or channel 21 is 65 in constant communication with a channel 22 preferably arranged in the wall of the casing 10. The channel 22 is preferably provided with a portion 23 into which a fluid inlet pipe discharges at 24, so that the 70 fluid entering the inlet 24 and being delivered into the portion 23 will pass from the channel 22 into the channel 21 in the element 17, to be discharged therefrom into the passages 20, and through suitable outlet openings 75 25 as indicated by the arrows in Fig. 1.

The element 17 is of a size somewhat less than the interior of the chamber 10 so that the portions 18 thereof will be spaced from the adjacent wall of the casing. Arranged 80 within the casing is a rotor designated generally by the reference numeral 26 in Fig. 1. This rotor is connected with the shaft 12 for rotation therewith by means of a suitable connecting device 27 and embodies a body 85 portion having a laterally projected circumferential portion 28 which encompasses the adjacent portion of the element 17. The rotor is shown as being provided with two blades 29. These blades 29 may be of any 90 desired length but are preferably of a considerable length arranged substantially spirally about the element 17 and with the inner ends of each blade overlapping the inner end of the next adjacent blade. 95 These blades 29 may be spaced from each other for any desired distance, and the ends or portions 29^a—29^b; 29^c—29^d, of the respective blades are arranged substantially concentric with the axis 12 of the rotor, while 100 the parts 29^a—29^b; and 29^c—29^d are substantially parallel so that when the rotor is set in motion the blades as they are advanced will move into the liquid to take up a portion thereof. The portion of the liquid thus taken up will be confined in the passage and will remain in a substantially quiescent condition with the result that as the rotor is further actuated the walls of the passage will advance with respect to the liquid confined in the passage and there will be little 110 centrifugal force or turbine action imparted

to the liquid, while at the same time the liquid will have a slight radial flow to be replaced by other supplies between the walls of the passage as the rotor operates. This 5 is due to the fact that the blades are arranged substantially parallel, are rotated at a very high rate of speed and are involutes of a circle, which circle is concentric with the shaft of the rotor. During this high 10 rate of speed of rotation of the rotor the liquid is admitted into the casing through the inlet 11 and as the blades of the rotor pass through the liquid, little centrifugal force or turbine action will be imparted to 15 the liquid but the liquid will move outwardly in a radial direction.

During this operation of the rotor, the inlets 30 of the passages between the blades 29 will successively pass the outlet openings 20 25 of the element 17, with the result that as the blades advance they will gradually close and open the outlets 25 and with the further result that slugs of air or fluid will be taken into the passages between the blades 25 alternately with the slugs of liquid and, as the blades advance and first cut into and are advanced with respect to the liquid, the liquid will move outwardly in a radial 30 direction and will be immediately delivered under pressure. As this pressure increases the liquid will be discharged from the casing.

Communicating with the casing is a volute passage 31 having a discharge outlet 35 32 and, if desired a partition 33 may be provided in this volute passage.

It will thus be seen that with this improved construction little centrifugal force or turbine action will be imparted to the liquid 40 and as the blades, or passages between the blades pass into and out of communication with the outlets 25 of the fluid passage, the fluid will be taken in between the slugs of water and the latter will be maintained 45 in as near its original shape as possible, as they will not be flattened out by throwing the slugs of water against the walls of the passage, with the result that friction is considerably reduced and at the same time the 50 portion of the passage between the slugs of liquid will be unobstructed and free from the liquid resulting in the full cylindrical area for the fluid so that the efficiency of the machine will be greatly increased.

55 Obviously any number of blades 29 forming passages therebetween may be provided.

With this construction and as the rotor is rotated the liquid contained in the space 17 will flow away from the axis 12 in a 60 radial direction, and as the blades advance with respect to the liquid therebetween the liquid will remain practically at rest.

It will therefore be manifest that the liquid will be subjected to little centrifugal or 65 turbine action.

If the rotor is incased within a housing having an inlet and an outlet for the liquid, the action of the rotor in the manner described will deliver the liquid to the housing under pressure at once with the minimum 70 velocity.

With this improved construction it will be manifest that the liquid will operate in the nature of a piston with this exception, that in the previous constructions the liquid piston is given velocity by the rotor, whereas in the present invention the liquid piston remains practically at rest while the rotor is in operation.

With this improved construction displacement will also be caused by the involute part of the blades and during the time that this part of the blade is passing the fluid opening. The liquid during this rotation of the rotor will be moving radially outward and acts as a wall between the fluid openings so that when the blade is passing the fluid opening the involute part of the blade will cause a displacement.

Obviously many changes may be made in the details of construction and in the combination and arrangement of the several parts within the scope of the claims without departing from the spirit of this invention and so long as the parts operate in a manner that the rotor will impart little centrifugal force or turbine action to the liquid.

What is claimed as new is:—

1. An apparatus of the character described embodying a casing having a liquid inlet and a discharge outlet, a rotor mounted in the casing, and means for imparting a high rate of speed of rotation to the rotor, said rotor embodying a plurality of blades extending from the periphery of the rotor inwardly and terminating short of the axis of rotation of the rotor, said blades being spaced to form fluid passages therebetween, the portions of proximate blades adjacent the outlets of the passages being substantially parallel and substantially concentric with the axis of rotation of the rotor, whereby little centrifugal force or turbine action will be imparted to the liquid as the rotor operates therein and the blades move therethrough.

2. An apparatus of the character described embodying a rotor having a high speed of rotation, said rotor embodying a plurality of blades arranged about the axis of rotation of the rotor and spaced therefrom, said blades being spaced from each other and cooperating to form liquid passages therebetween, the portion of proximate blades adjacent the outlets of the passages being in substantially parallel circles concentric with the axis of rotation of the rotor, whereby little centrifugal force or turbine action will be imparted to the liquid as the rotor operates therein and the blades move therethrough.

through, and a conduit having an outlet opening adjacent the path of movement of the inlets of said passages, the relative movement of the liquid and the said passages operating to create a suction in the said conduit.

3. An apparatus of the character described embodying a rotor having a high speed of rotation, said rotor embodying a plurality of blades arranged about the axis of rotation of the rotor and spaced therefrom, said blades being spaced from each other and co-operating to form liquid passages therebetween, the portion of proximate blades adjacent the outlets of the passages being in substantially parallel circles and concentric with the axis of rotation of the rotor, whereby the liquid between the blades will be maintained in a substantially quiescent condition and substantially no centrifugal or turbine action will be imparted to the liquid between the blades as the blades and the liquid therebetween are displaced relatively one with relation to the other.

25 4. An apparatus of the character described embodying a rotor having a high speed of rotation, said rotor embodying a plurality of blades arranged spirally about the axis of rotation of the rotor, said blades having portions forming substantially parallel circles and co-operating to form fluid passages therebetween, the said portions being concentric with the axis of rotation of the rotor whereby the fluid in the said passages will be maintained substantially quiescent as the blades and fluid therebetween are displaced relatively one with relation to the other and whereby substantially no centrifugal or turbine action will be imparted 40 to the fluid between the blades and the fluid will be displaced radially with respect to the axis of the rotor.

5. An apparatus of the character described embodying a rotor having a high speed of rotation, said rotor embodying a plurality of blades arranged spirally about the axis of rotation of the rotor, said blades having portions forming substantially parallel circles and co-operating to form fluid passages therebetween, the said portions being concentric with the axis of rotation of the rotor whereby the fluid in the said passages will be maintained substantially quiescent as the blades and fluid therebetween are displaced relatively one with relation to the

other and whereby substantially no centrifugal or turbine action will be imparted to the fluid between the blades and the fluid will be displaced radially with respect to the axis of the rotor, and means whereby the fluid may be introduced axially to said rotor.

6. An apparatus of the character described embodying a rotor having a high speed of rotation, said rotor embodying a plurality of blades arranged spirally about the axis 65 of rotation of the rotor, said blades having portions forming substantially parallel circles and co-operating to form fluid passages therebetween, the said portions being concentric with the axis of rotation of the 70 said rotor, whereby the fluid in the said passages will be maintained substantially quiescent as the blades and fluid therebetween are displaced relatively one with relation to the other and whereby substantially no centrifugal or turbine action will be imparted to the fluid between the blades and the fluid will be displaced radially with respect to the axis of the rotor, and a volute chamber 75 in which the said rotor operates, said chamber having an inlet opening and an outlet opening for the fluid.

7. An apparatus of the character described embodying a rotor having a high speed of rotation, said rotor embodying a plurality of blades arranged spirally about the axis 85 of rotation of the rotor, said blades having portions forming substantially parallel circles and co-operating to form fluid passages therebetween, the said portions being 90 concentric with the axis of rotation of the rotor whereby the fluid in the said passages will be maintained substantially quiescent as the blades and fluid therebetween are displaced relatively one with relation to the 95 other and whereby substantially no centrifugal or turbine action will be imparted to the fluid between the blades and the fluid will be displaced radially with respect to the axis of the rotor, a volute chamber in 100 which the said rotor operates, said chamber having an inlet opening and an outlet opening for the fluid, and one or more partitions in the chamber dividing the same into fluid passages.

105 In testimony whereof I have signed my name to this specification on this 7th day of July, A. D. 1919.

BENJAMIN SKIDMORE, Jr.
